UNITED STATES PATENT OFFICE.

CARBON P. DUBBS, OF WILMETTE, ILLINOIS, ASSIGNOR TO THE UNIVERSAL OIL PRODUCTS COMPANY, OF CHICAGO, ILLINOIS, A CORPORATION OF SOUTH DAKOTA.

PROCESS FOR CRACKING PETROLEUM OIL.

Application filed March 9, 1923, Serial No. 623,988. Renewed June 15, 1927.

This invention relates to a process for cracking petroleum oil, and refers more particularly to that type of process in which the oil is passed through a suitable heating furnace preferably in a relatively small stream, as for example, through a preheating coil and thence to an expansion chamber where vaporization takes place, and a separation is made of the vapors and residue.

It is of course, known to those skilled in the art, that one of the principal difficulties in the cracking process heretofore, has been in the handling of the carbon containing residue in such a manner as to obtain a maximum yield of gasoline without all too often having to shut down the plant because of it becoming choked with carbon or because of hot spots developing from carbon, or the apparatus being subjected to fires or danger of explosion.

At the same time the cracking process is in its last analysis one of economy, namely being able to make the desired gasoline or other product with a minimum cost. To do this, it is desirable to crack as large a percentage of the oil into gasoline as is practicable. Accordingly, it is desirable to retreat the residue, but care must be taken not to retreat the residue in such quantities and of such a character as to choke up the heating tubes. Also different kinds of oils must be treated in a different manner, and it is obvious that the average small independent refiner cannot afford to build a cracking plant for each separate oil he has to treat, due to the various crudes or the different cuts of the crude as for example, kerosene, gas oil and fuel oil.

To this end, it is desirable to have an apparatus and process which will have as much flexibility as is possible, bearing in mind the necessity of retaining the economy in operation and simplicity of construction.

The object of the invention is to give the independent or small refiner such a process and apparatus, and it may here now be stated that the process hereinafter described is in no sense necessarily confined to the particular type of apparatus hereinafter set forth, although I believe that the apparatus itself contains substantial patentable novelty.

In order to understand the invention, I have shown the accompanying drawing in

which the single figure is a somewhat diagrammatic representation of my improved apparatus, and I also wish to state that the parts there shown are not in any sense shown to scale or proportion, but the relative proportions of heating tubes, expansion chambers, dephlegmators and the like are too well known to those skilled in the art to necessitate any detailed description at this day.

Referring to the drawing, 1 designates a furnace in which is mounted the heating coil 2 which may take the form of a plurality of two to six inch tubes, preferably connected in series, although if desired, the coils may be connected in multiple. The oil enters the heating coil through the charging line 3 having a throttle valve 4 connected to the feed pump 5, the inlet side of the pump being connected to pipe 6 having a throttle valve 7 to storage tank 8, hereinafter referred to.

The oil heated to the desired temperature, passes through transfer line 8' having throttle valve 9 into the first of a series of tanks 10, 11, 12 and 13 respectively. These tanks are connected by the liquid overflow lines 14 each having suitable throttle valves 15 whereby if desired, a differential pressure may be maintained on the tanks. The tanks may also be provided with vapor connection pipes 16, 17 and 18 having suitable throttle valves 19, 20 and 21 respectively.

Instead of passing the vapors serially through the tanks, they may be taken off from the top of each tank through pipes 22 controlled by throttle valves 23, the pipes 22 leading to a manifold pipe 24 having a throttle valve 25 and connected to the vapor pipe 26 leading from the top of the last tank 13. The pipe 26 communicates with the lower end of the dephlegmator, and may be provided with a throttle valve 28, if desired. The upper end of the pipe 26 is covered with a spaced cap member 29, the arrangement being such as to permit vapors to enter the lower end of the dephlegmator 27 while preventing the reflux condensate from falling back into the chamber 13. As the vapors enter the dephlegmator 27, they are subjected to a reflux condensing action and the reflux condensate is drawn off through the pipe 30 controlled by a throttle valve 31 back to the feed line 3. The uncondensed vapors pass out of the top of the

dephlegmator through the pipe 32 controlled by the throttle valve 33 to the water condenser 34 connected to the receiver 35, which receiver is equipped with gas outlet

- pipe 36 having a throttle valve 37 and a liquid drawoff pipe 38 having a throttle valve 39.

The arrangement is such that a uniform pressure may be maintained on the system or 10 a differential pressure may be maintained by regulating the valves shown.

Referring now particularly to the tanks 10 to 13 inclusive, they may be insulated and located entirely outside of the fire zone, or if

- 15 desired, they may be located in a suitable fire setting 40 where they may be heated as a whole, or they may be individually heated by suitable burners, not shown, so as to have a uniform temperature in the tanks, which 20 temperature may be gradually increased or decreased depending upon conditions.

Referring now more particularly to the manner of handling the residue in these tanks, as heretofore stated the character of 25 the residue will vary with the extent to which the process is pushed, the character of the oil treated, as for example, whether it has a paraffin base or an asphaltic base, and also upon the particular cut of the oil from 30 any of these crudes which may be taken.

It may therefore be desirable to retreat part of the residue but not necessarily all of it, and it may be desirable to make rather fine differentials as to what particular type 35 of the residue it is desired to treat.

To this end the tanks 10, 11, 12 and 13 are provided with liquid drawoff lines 41 each controlled by suitable throttle valves 42, which may lead to a suitable manifold pipe 40 43 having a throttle valve 44 and leading to a combined storage and settling tank 45, which tank 45 is provided with a suitable overflow pipe 46 having a valve 47 whereby the residue may be delivered in regulated 45 quantities to the storage charging tank 8. The tank 45 may have a carbon drawoff pipe 48 controlled by a valve 49, whereby the heaviest part of the residue may, if desired, be prevented from entering the tank 8. As 50 shown clearly in the drawing, the residue from any of the tanks 10, 11, 12 or 13 may be by-passed and prevented from entering the tank 45 by means of by-pass lines 50 each having a throttle valve 51. While, it is of 55 course desirable to re-crack as much of the residuum as possible, it is also desirable to so regulate the character of the residue and the quantity of it relative to the raw oil charging stock to secure the most effective 60 results.

It is apparent that this can be accomplished very readily by means of the method and apparatus above described. The combined charging stock may be fed by means 65 of the pump 5 and the line 52 having a

throttle valve 54 to the upper end of the dephlegmator, where it serves to cool the vapors and at the same time preheat the charging stock.

The combined reflux condensate and 70 charging stock may be drawn off through the pipe 30 and passed to the tubes. If desired, however, the dephlegmator may be bypassed as far as the charging stock is concerned, and the latter delivered direct by the 75 pump 5 through the feed line 3 to the coil 2, the valve 54 in the line 52 being then closed.

In carrying out the process, the oil may be subjected to a pressure of from 100 pounds 80 upwards, if desired, and the oil so cracked as to convert from 50% to 75% or more into gasoline of say 400 end point.

The extent to which the cracking takes place, and the amount of total gasoline 85 cracked, can be very effectively regulated by means of the present invention.

I claim as my invention:

1. A process for cracking oil consisting 90 in passing the oil through a heating coil, thence to a plurality of enlarged chambers connected in series and allowing vaporization to take place in said chambers and withdrawing the vapors therefrom, withdrawing the liquid residue from each of said chambers independently and diverting predetermined quantities of said residue from predetermined chambers back to the charging stock and commingling the same with said charging stock and sending said mixture through the heating coil to be cracked and maintaining a superatmospheric pressure on the oil during treatment.

2. A process for cracking oil consisting 105 in passing the oil through a heating zone preferably in a relatively small stream, thence to a plurality of enlarged chambers connected in series and allowing vaporization to take place in said chambers and withdrawing the vapors therefrom, withdrawing 110 the liquid residue from each of said chambers independently and diverting predetermined quantities of said residue from predetermined chambers back to the charging stock and commingling the same with 115 said charging stock and sending said mixture through the said heating zone to be cracked and maintaining a super-atmospheric pressure on the oil during treatment.

3. A process for cracking oil consisting in 120 passing the oil through a heating zone preferably in a relatively small stream, thence to a plurality of enlarged chambers connected in series, the temperature of said chambers being controlled relative to the 125 temperatures in the small stream, and allowing vaporization to take place in said chambers, withdrawing the vapors therefrom, withdrawing the liquid residue from each of said chambers independently and divert- 130

ing predetermined quantities of said residue from predetermined chambers back to the charging stock and commingling the same with said charging stock and sending 5 said mixture through the heating zone to be cracked, and maintaining a super-atmospheric pressure on the oil during treatment.

4. A process for cracking oil consisting in passing the oil through a heating coil, 10 thence to a plurality of enlarged chambers connected in series, the temperature of said chambers being controlled relative to the temperatures in the heating coil, and allowing vaporization to take place in said chambers, and withdrawing the vapors therefrom, withdrawing the liquid residue from 15 each of said chambers independently and diverting predetermined quantities of said residue from predetermined chambers back 20 to the charging stock and commingling the same with said charging stock and sending

said mixture through the heating coil to be cracked and maintaining a superatmospheric pressure on the oil during treatment.

5. A process for cracking oil comprising 25 passing the oil through a heating zone, thence to a plurality of enlarged zones arranged in series, controlling the temperature of said enlarged zones relative to the temperature of the heating zone, effecting 30 vaporization of oil constituents in said enlarged zones, removing the vapors therefrom, selectively withdrawing liquid residue from each of said enlarged zones, diverting predetermined portions of the liquid residue withdrawn from predetermined enlarged zones 35 back to the heating zone to commingle with charging oil for the process and be subjected to further cracking, and maintaining controlled superatmospheric pressure on the oil 40 undergoing treatment in the process.

CARBON P. DUBBS.
